FLUID ACTUATED PERCUSSIVE TOOL

Filed Oct. 11, 1928

FIG. 2 INVENTOR.
Francis A. Jimerson.

BY *Asbury D. Allen*

HIS ATTORNEY.

FIG. 1.

UNITED STATES PATENT OFFICE

FRANCIS A. JIMERSON, OF ATHENS, PENNSYLVANIA, ASSIGNOR TO INGERSOLL-RAND COMPANY, OF JERSEY CITY, NEW JERSEY, A CORPORATION OF NEW JERSEY

FLUID ACTUATED PERCUSSIVE TOOL

Application filed October 11, 1928. Serial No. 311,775.

This invention relates to fluid actuated percussive tools, but more particularly to a valve action for the type of tool known as semi-valveless in which the admission of pressure fluid to the rear end of the cylinder is controlled by a fluid actuated valve while the admission of fluid for driving the piston rearwardly is controlled by the piston.

The objects of the present invention are to obtain an inlet valve which is quick and positive in action and which will increase the speed of the piston travel and be sensitive to, and effectively controlled by pressure fluid.

Another object is to construct a valve which will permit the exhaust of pressure fluid from the rear end of the cylinder through the valve and thus increase the efficiency of the tool.

Other objects of the invention will herein-after appear and to all of these ends the invention is shown in the accompanying drawings, in which:

Figure 1 is a longitudinal cross sectional view of so much of a pneumatic tool as will show the piston and valve in their rearmost positions and

Figure 2 is a view similar to Figure 1 showing the piston and the valve in their forward-most positions.

Referring more particularly to the drawings A is the cylinder of a pneumatic tool having a hammer piston B. The piston B has a reduced forward extension C adapted to fit slidably in the correspondingly reduced portion D of the cylinder A. The forward end of the cylinder is closed by a front cylinder washer E bored to receive the shank F of a working implement (not shown). A back head G forms a closure for the rearward end of the cylinder and interposed between the back head G and the cylinder A is a plate H.

The back head G is bored longitudinally to receive a valve bushing J. A transverse slot K is adapted to receive a yoke bar L which forms part of the handle fastening mechanism which will not be described since it forms no part of this invention. A valve O fits slidably in the valve bushing J and acts as a semi-automatic throttle valve for the tool. The operation of the valve O is coop-

erative with the handle P; that is when the workman pushes downwardly upon the handle P the valve O is forced down against the upward force of the pressure fluid in the small chamber Q in the valve bushing J. A leak port R constantly admits pressure fluid to the chamber Q from the hose S and when the workman presses downward upon the handle P the valve O moves downward bringing a ring groove T on the valve O into such a position that pressure fluid may pass freely from the hose into a passage U. When pressure is released from the handle the pressure fluid in the chamber Q forces the valve upward thus throwing the ring groove out of connection with the passage U and the hose S. A sliding fit is maintained between a sleeve V on the handle P and the back head G. This type of handle construction is fully described in the patent to F. A. Jimerson No. 1,160,617.

A valve chamber W is formed in the forward end of the back head G and a valve X is mounted therein. The valve X is of substantially cylindrical shape and a ring groove Y is formed intermediate its ends. A passage Z is formed transversely through the valve and this passage has its ends in the ring groove Y. A short longitudinal passage b connects the passage Z with the forward face of the valve X. An annular groove c is formed within the valve chamber W and a second annular groove d formed partly in the back head G and partly in the plate H permits communication between the passage U and the valve chamber W. A leak port e leads from the groove c to atmosphere. A short passage f formed in the plate H affords communication between the chest W and the rearward end of the cylinder A.

The ports and passages not yet mentioned may be more easily described in connection with the operation of the tool, which is as follows:

Assuming the movable parts of the tool to be in the position shown in Figure 1 live air is admitted through the throttle valve and enters the passage U. From the passage U pressure fluid enters the valve chamber d, having forced the valve upward by pressure

exerted on the exposed lower face *g* which projects into the chamber *d*. Pressure fluid then passes through the port *f* and into the cylinder *A* behind the piston *B* forcing the piston forward on its working stroke. As the piston advances the striking end *B'* closes a port *h* and ring grooves *j* and *k* in the striking end *B'* successively admit pressure fluid from a passage *q* into a port *o* which opens into a passage *p* in the cylinder *A*. The pressure fluid thus admitted to the passage *p* will travel up to the rear end of the valve *X*, filling the chamber *W* and forcing the valve down onto its front seat. The closing of the valve will take place regardless of the fact that the area beneath the valve exposed to fluid pressure is greater than the initial area exposed to fluid pressure on the top of the valve; for the pressure under the valve is less than full line pressure due to the forward movement of the piston, whereas the pressure on the upper surface is substantially full line pressure. Upon continuing its forward motion the piston will uncover an exhaust port *r* permitting the rearward end of the cylinder to exhaust to the atmosphere. At the same time a ring groove *s* in the striking end *B'* of the piston connects the passage *q* with a chamber *t* permitting live pressure fluid to act against a shoulder *u* on the piston *B*. The piston will then start on its return stroke and after the exhaust port *r* is closed the compression is relieved through the passages *z*, *b*, *Z* and *e*. The valve *X* will remain closed until the striking end of the piston uncovers port *h*, whereupon pressure on the rear end of the valve will be relieved due to the fact that a chamber *v*, formed in the lower end of the cylinder *A*, will exhaust to the atmosphere by way of a passage *w*, ring groove *s* and exhaust ports *r* and *r'*. The cycle of operations is again started by the lifting of the valve *X*. In practice the device above described is quick and positive in action and economical in the consumption of pressure fluid.

I claim:

1. In a fluid actuated percussive tool, the combination of a cylinder having a reciprocating piston and an exhaust port located intermediate the ends of the cylinder, a valve chest and a fluid actuated inlet valve having a ring groove around its central portion, a port passing transversely through the valve and communicating at both ends with said ring groove, a longitudinal port communicating with the front end of said valve and with the said transverse port, a passage leading through the wall of the cylinder from an annular groove in said valve chest, said annular groove being adapted to cooperate with the ring groove and the longitudinal passage in said valve for relieving compression from the rearward end of the cylinder, a passage communicating with the valve chest

and with the rearward end of said cylinder, a second passage communicating with the valve chest and with the cylinder at a point between the front end of the cylinder and the exhaust port, said first passage being controlled by said valve and admitting pressure fluid to the rear end of the cylinder, said second passage being controlled by the piston and admitting pressure fluid to the front end of the cylinder, a third passage in said cylinder leading from the front end of the cylinder to the rearward end of said valve chest, grooves in said piston providing communication between said second passage and said third passage for carrying pressure fluid to the rear end of said valve chest to throw said valve forwardly to close the passage leading from the valve chest to the rearward end of the cylinder.

2. In a fluid actuated percussive tool, the combination of a cylinder and a reciprocable piston, a main exhaust port controlled by the piston for exhausting the cylinder from both ends of the piston, a valve chest having a valve chamber, an inlet passage leading from one end of the valve chamber to the rear end of the cylinder, a supply chamber at the same end of the valve chamber and in constant communication with a source of pressure fluid supply, a reciprocatory valve in the valve chamber actuated in one direction by the pressure fluid in said supply chamber to admit pressure fluid therefrom to the inlet passage, an auxiliary exhaust port in the valve chest, passages in the valve adapted to register with said auxiliary exhaust port and the inlet passage to relieve compression from the rear end of the cylinder, a second inlet passage controlled by the piston for intermittently supplying pressure fluid to the front end of the cylinder, and a passage controlled by the piston for intermittently supplying pressure fluid to the opposite end of the valve chamber to return the valve.

3. In a fluid actuated percussive tool, the combination of a cylinder having a piston chamber and a reduced bore, a differential piston reciprocable in the piston chamber and the reduced bore, an exhaust port in the piston chamber controlled by the piston, a valve chest having a valve chamber, an inlet passage leading from one end of the valve chamber to the rear end of the cylinder, a supply chamber opening into the same end of the valve chamber and in constant communication with a source of pressure fluid supply, a valve in the valve chamber controlling communication between the supply chamber and the inlet passage, a second inlet passage leading from the supply chamber to the reduced bore, a groove in the piston adapted to register with said inlet passage and the front end of the cylinder, a passage leading from the reduced bore to the opposite end of the valve chamber, and a second groove in the piston

forwardly of the first said groove for establishing communication between the second inlet passage and the last said passage to actuate the valve to the closed position.

4. In a fluid actuated percussive tool, the combination of a cylinder and a reciprocable piston, an exhaust port in the cylinder controlled by the piston, a valve chest having a valve chamber, an inlet passage leading from one end of the valve chamber to the rear end of the cylinder, a supply chamber opening into the same end of the valve chamber as the inlet passage and being in constant communication with a source of pressure fluid supply, a reciprocatory valve in the valve chamber actuated in one direction by the pressure fluid in the supply chamber to admit the pressure fluid therefrom to the inlet passage, a second inlet passage controlled by the piston for intermittently supplying pressure fluid to the front end of the cylinder, and a passage controlled by the piston for intermittently supplying pressure fluid from the front end of the cylinder to the opposite end of the valve chamber to return the valve.

5. In a fluid actuated percussive tool, the combination of a cylinder and a reciprocable piston, an inlet passage controlled by the piston for supplying motive fluid to the front end of the cylinder, a valve chest having a valve chamber, a second inlet passage leading from one end of the valve chamber to the rear end of the cylinder, a valve in the valve chamber movable to one position to admit motive fluid through the second inlet passage to the rear end of the cylinder, said motive fluid holding the valve in said position, and a passage controlled by the piston for intermittently supplying motive fluid from the front end of the cylinder to the valve chamber to act in opposition to the motive fluid holding the valve in said position and thereby return the valve.

In testimony whereof I have signed this specification.

FRANCIS A. JIMERSON.
